UNITED STATES PATENT OFFICE

91,335

DESIGN FOR A CABINET FOR A GAME TABLE

Harry B. Stoner, Aurora, Ill.

Application October 18, 1933. Serial No. 49,511

Term of patent 7 years

To all whom it may concern:

Be it known that I, HARRY B. STONER, a citizen of the United States, residing in the city of Aurora, in the county of Kane and State of Illinois, have invented a new, original, and ornamental Design for a Cabinet for a Game Table, of which the following is the specification, reference being had to the accompanying drawing forming a part thereof.

On the drawing:

The figure is a perspective view of a cabinet for a game table embodying my invention.

I claim:

The ornamental design for a cabinet for a game table as shown.

HARRY B. STONER.
